UNITED STATES PATENT OFFICE.

JOSEPH SUTTER, OF NEW YORK, N. Y.

DESIGN FOR A CHAIR.

SPECIFICATION forming part of Design No. 12,993, dated June 20, 1882.

Application filed May 8, 1882. Term of patent 14 years.

To all whom it may concern:

Be it known that I, JOSEPH SUTTER, of the city and State of New York, have invented or produced a Design for a Chair, of which the following is a specification.

5 This chair is provided with a base, arms, and a back, and the ornaments thereon are represented in the accompanying drawings, in which—

10 Figure 1 is a front elevation, showing the base and the back ornaments; and Fig. 2 is a side view, showing especially the arms.

The base is made with a border, *a*, cross-bar ornaments *b* in relief, a scroll-work border, *c*, 15 at the bottom, and an eagle in low relief, as at *f*.

The sides of the base are ornamented in the same manner, only there is a star, *g*, in the panel below the cross-bars *b*. The back of the base should be similarly ornamented.

20 The arms are composed of the scroll-shaped front pieces, *g'*, with raised borders and a head at the upper end. The top pieces of the arms are curved, with raised borders and cross-pieces, as at *h*, and there is a leaflet-support at *k*, and

25 at the junction of the back leg and arm the border-pieces extend across each other and terminate with rounded ends, as at *l*.

The chair-back is made with a frame of open-work strips *n* and cross-bar pieces *o*, and the 30 open-work at the top of the back is similar to

curved pieces, crossing each other and interlaced, as represented.

At the top angles of the chair-back the open-work represents the strips as crossing each other and the ends rounding and projecting, 35 as shown. There are cross-pieces at *r* in the otherwise open spaces at the top of the back.

I claim as my invention—

1. The design of the ornaments upon the chair-base, consisting of the raised borders 40 and cross-pieces, substantially as set forth.

2. The design of the ornaments upon the chair-base, consisting of the raised borders, cross-pieces, and eagle in low relief, as set forth.

45 3. The design of the chair-arms, consisting in the outline shape represented and the borders, cross-pieces, and end pieces, as described and shown.

4. The design of the ornamental shape of 50 the chair-back, consisting of the bars with intervening open-work, cross-bars, and projecting curved ends of the bars, substantially as set forth.

Signed by me this 4th day of May, A. D. 1882. 55

JOSEPH SUTTER.
